CLAIM

The ornamental design for a padded sock, as shown and described.

DESCRIPTION

FIG. 1 is a perspective view of a padded sock in accordance with my new design, the various padded portions being shown in stippled shading;

FIG. 2 is a side elevational view thereof, the opposite side being substantially identical;

FIG. 3 is a front elevational view thereof;

FIG. 4 is a rear elevational view thereof;

FIG. 5 is a top plan view thereof; and,

FIG. 6 is a bottom view thereof.
